UNITED STATES PATENT OFFICE.

IRA BISHOP AND ARTHUR F. L. BELL, OF SAN FRANCISCO, CALIFORNIA.

AUTOMATIC TRAP FOR CABLE-CONDUITS.

SPECIFICATION forming part of Letters Patent No. 478,910, dated July 12, 1892.

Application filed January 29, 1892. Serial No. 419,709. (No model.)

To all whom it may concern:

Be it known that we, IRA BISHOP and ARTHUR F. L. BELL, citizens of the United States, residing in the city and county of San Francisco, State of California, have invented an Improvement in Automatic Traps for Cable-Railway Tubes; and we hereby declare the following to be a full, clear, and exact description of the same.

10 Our invention relates to the class of cable railways, and especially to the traps or openings in the tubes or tunnels thereof and through which the grips are intended to be removed from and replaced in the tube or 15 tunnel.

Our invention consists, essentially, in openings into the tube or tunnel, controlled by doors or covers, and suitable connections therewith actuated by the car to operate said 20 doors or covers to expose and to close said openings.

It also consists in novel guides within the tube or tunnel to direct the descending grip to position over the cable.

25 It also consists in the novel constructions, combinations, and arrangements hereinafter fully described, and specifically pointed out in the claims.

It is usual in cable railways to provide openings in the top of the tube or tunnel at suitable intervals, through which the grip can be removed and replaced. The necessity for using these openings has not heretofore been very great, because the reasons for removing the

35 grip have been few, such as to readjust or to repair it. Consequently the doors or covers of the openings have always been manipulated by hand; but in some roads the grip has to be removed oftener and for other reasons—as,

40 for example, where there are sections of the road over which the car travels by gravity and there is no need to keep the grip in the tube, or, in fact, where there is no tube at all. In such cases, therefore, the grip has to be re-

45 moved and replaced, it may be, several times during each trip. It then becomes of importance to provide means for easily uncovering said openings; and it is the object of our invention to provide such means. This object

50 we attain by the provision of means for automatically accomplishing the result, which result is due to the arrival of the car itself at

the point where it is necessary to uncover the tube or tunnel.

Referring to the accompanying drawings 55 for a more complete explanation of our invention, Figure 1 is a cross-section of a cable-railway tube, showing our automatic grip-trap. Fig. 2 is a side elevation of same.

A is the tube or tunnel of a cable railway. 60 B are the slot-irons in its top, and C are the ordinary track-rails of the road-bed.

At the point where an opening (designated by a) is to be the ordinary slot-irons are omitted, and in their places are substituted the 65 plates D, which at this place not only form the slot, but also constitute the doors or covers of the opening.

Above the plates D on each side may be placed longitudinal separated stringers X, 70 which are on the roadway level and serve as a partial roof or housing over the plates, and to these stringers brace-strips Y may be secured.

The cover or door plates are carried upon 75 the tops of levers E, which are pivoted at the points e. To the lower end of one of these levers, here shown as the one on the right, is connected an arm F, the outer end of which carries a weight W. The normal action of 80 this weight is to keep the lever E in an upright position, in which its door-plate is held inwardly to close the opening, and said lever is limited in its inward movement by the weight resting in the bottom of the pit or of 85 any support therein.

G is a three-armed bell-crank lever pivoted at g. The upper arm of this lever is connected with the left-hand lever E by a link H, the connection being an adjustable one, as 90 shown. The inner arm of lever G is connected with the weighted arm F by a link I. Thus the action of the weight W is to keep the left-hand lever E in an upright position to hold its door or cover plate D closed over 95 the opening, and said lever E is limited by the weight, resting as before mentioned. Thus the normal position of the door or cover plates is a closed one in which they continue the slot and cover the opening or trap into the tube 100 or tunnel, and when moved from this position they will return to it as soon as the moving cause is withdrawn.

The power for operating the plates D is the

car itself. Any suitable connection may be employed to effect this, and said connections may be operated by any portion of the car, as by contact with its grip or with a projection 5 or arm on the car; but we prefer to operate through the wheels of the car, as follows: Behind and separated from one of the track-rails C is a guide-rail J, which is bolted to the rail near each end. In the space or pocket 10 formed between the track-rail and the guide-rail is seated a presser-lever K, which at one end is pivoted at k. This lever rises above the track and guide rails in a gradually-increasing inclined plane to its free end, so that 15 the wheels of the car will run it down and depress it. On the under side of this presser-lever at a suitable point is a lug k', and with this is connected a link L, the lower end of which is connected to the outer arm of the lever G.

In the drawings the plates D are shown as being below the slot-irons; but this is not essential and is only due to the presence of the roof-stringers X, under which they work, said 25 stringers being on the road-level. If these stringers were not present, the cover-plates D could be placed on a level with the slot-irons.

The operation is as follows: When the car reaches the presser-lever K, its wheels depress 30 said lever, and through the lever G and its connections the two upright levers E are thrown backwardly, thereby separating the door or cover plates D and exposing the opening in the top of the tube or tunnel, through 35 which the grip can be removed or can be replaced, if previously removed. As soon as the car passes from and relieves the presser-lever the weight W will return the parts to their normal position.

40 It is well in replacing the grip to provide some means for accurately guiding it down to position to take the cable. These means consist of the fixed separated guide-bars M, located and supported suitably in the tube or 45 tunnel. The descending grip N is received between and guided properly by these bars to position over the cable O.

Having thus described our invention, what we claim as new, and desire to secure by Letters 50 Patent, is—

55 1. In a cable railway having a tube or tunnel provided with an opening for the removal and insertion of the grip from and into said tube or tunnel, a door or cover controlling said opening, and connections with said door or cover actuated by the car to operate it and cause it to expose and cover said opening, substantially as herein described.

60 2. In a cable railway having a tube or tunnel provided with an opening in its top for the removal and insertion of the grip-frame from and into said tube or tunnel, a swinging door or cover controlling said opening, and connections with said door or cover actuated by the 65 car to swing the door or cover open and closed, substantially as herein described.

3. In a cable railway having a tube or tunnel provided with an opening in its top for the removal and insertion of the grip-frame from and into said tube or tunnel, a door or cover 70 controlling said opening, a lever in the roadway actuated by the car, and connections between said lever and the door or cover, whereby the latter is operated to expose and cover the opening, substantially as herein described. 75

4. In a cable railway having a tube or tunnel provided with an opening in its top, the opposing plates D, separated to form the slot and constituting the door or cover of the opening, and connections actuated by the car 80 to throw said plates from and toward each other to expose and cover the opening, substantially as herein described.

5. In a cable railway having a tube or tunnel provided with an opening in its top, the 85 opposing plates D, separated to form the slot and constituting the door or cover of said opening, a lever in the roadway above actuated by the car, and connections between said lever and the plates D to throw them from 90 and toward each other to expose and cover the opening, substantially as herein described.

6. In a cable railway having a tube or tunnel provided with an opening in its top, the combination of the opposing separated plates 95 D, controlling said opening, the pivoted levers E, upon which said plates are carried, connections with said levers actuated by the car for moving them from each other to cause their plates D to expose the opening, and a weight 100 to return them to cover the opening, substantially as herein described.

7. In a cable railway having a tube or tunnel provided with an opening in its top, the combination of the opposing separated plates 105 D, controlling said opening, the pivoted levers E, by which said plates are carried, a lever above actuated by the car, and connections between said lever and the levers E, whereby the latter are separated to cause their plates 110 to expose the opening, and a weight to return them to close the opening, substantially as herein described.

8. In a cable railway having a tube or tunnel provided with an opening in its top, the 115 combination of the opposing separated plates D, controlling said opening, the pivoted levers E, by which said plates are carried, the weighted arm F, connected with one of said levers, the bell-crank lever connected with 120 said weighted arm and with the other of said levers, and connections with said bell-crank lever actuated by the car above to operate it, substantially as herein described.

9. In a cable railway having a tube or tunnel provided with an opening in its top, the combination of the opposing plates D, controlling said opening, the pivoted levers E, by which said plates are carried, the weighted arm F, connected with one of said levers, the 125 bell-crank lever connected with said weighted arm and with the other of said levers, the piv-

oted presser-lever in the roadway above, adapted to be actuated by the car-wheels, and the link connecting said presser-lever with the bell-crank lever, substantially as herein described.

5 10. In a cable railway having a tube or tunnel provided with an opening in its top to permit the removal and insertion of the grip, the fixed separated guide-bars in said tube or tunnel for directing the descending grip to posi-

tion to take the cable, substantially as herein described.

In witness whereof we have hereunto set our hands.

IRA BISHOP.
ARTHUR F. L. BELL.
